(57) **CLAIM**

The ornamental design for a storage tray with cover, as shown and described.

DESCRIPTION

The nature and intended use of the article being an ornamental design for a storage tray having a cover so that food on the tray may be easily stored.

FIG. 1 is a front elevational view of the storage tray with cover of the present invention, the rear elevational view being a mirror image thereof;

FIG. 2 is a left side elevational view of the storage tray with cover of FIG. 1, the right side elevational view being a mirror image thereof;

FIG. 3 is a top plan view of the storage tray with cover of FIG. 1; and,

FIG. 4 is a bottom plan view of the storage tray with cover of FIG. 1.
